(57) **CLAIM**

The ornamental design for a rocker runner for chairs, as shown and described.

DESCRIPTION

FIG. 1.1 is a front view of a rocker runner for chairs;

FIG. 1.2 is a back view thereof;

FIG. 1.3 is a left view thereof;

FIG. 1.4 is a right view thereof;

FIG. 1.5 is a top view thereof;

FIG. 1.6 is a bottom view thereof;

FIG. 1.7 is a top perspective view thereof; and

FIG. 1.8 is a bottom perspective view thereof.

The product is used to be mounted on the feet of a chair to form a rocking chair.
